FLUORESCENT EMERGENCY LIGHT

Richard Hughes and Thomas M. Steinbach, Park Ridge, Ill., assignors to Teledyne Big Beam Division, Teledyne Mid-America Corporation, Crystal Lake, Ill.

Filed Aug. 30, 1971, Ser. No. 176,430

Term of patent 14 years

Int. Cl. D26—05

U.S. Cl. D48—20 E

FIG. 1 is a perspective view of a fluorescent emergency light, showing our new design;

FIG. 2 is a side view thereof; and

FIG. 3 is a bottom view thereof.

The back is plain. The side which is not shown is the same as the side that is shown and the top is the same as the bottom.

We claim:

The ornamental design for fluorescent emergency light, as shown and described.
